UNITED STATES PATENT OFFICE.

WILLIAM C. MUENCH, OF INDIANAPOLIS, INDIANA, ASSIGNOR TO PROGRESS MACHINE CO., OF INDIANAPOLIS, INDIANA, A CORPORATION.

BOTTLE-FEEDING MECHANISM.

1,112,155.

Specification of Letters Patent. Patented Sept. 29, 1914.

Application filed May 6, 1912. Serial No. 695,493.

To all whom it may concern:

Be it known that I, WILLIAM C. MUENCH, a citizen of the United States, and a resident of Indianapolis, county of Marion, and State of Indiana, have invented a certain useful Bottle-Feeding Mechanism; and I do hereby declare that the following is a full, clear, and exact description thereof, reference being had to the accompanying drawings.

The object of this invention is to provide means in connection with a bottle crowning or capping machine for accurately feeding the filled bottles thereto and with considerable speed thus decreasing the cost of operation and increasing the efficiency of the machine.

One feature of the invention consists in combining with a star wheel and conveyer guide, a yielding bottle guide curved concentric with the star wheel and pivoted at one end so that the bottle guide will project away from the pivot in a direction opposite to the direction in which the bottle travels and at its free end the bottle guide is held by the conveyer guide further away from the star wheel than at the pivot point thereof so as to furnish the bottles or the like a wider entrance and cause them to turn or roll as they travel toward and into a pocket of the star wheel. Along with the foregoing feature is the further feature of pivoting the above yielding bottle guide to an adjustable bottle guide for holding the bottles from escaping from the star wheel during the remainder of the feeding movement.

The features of the invention will be understood from the accompanying drawings and the following description and claims:

In the drawings; Figure 1 is a perspective of a crowning machine with my invention installed thereon and with portions broken away. Fig. 2 is a plan view of the same with portions removed. Fig. 3 is a front elevation of the bottle guiding means. Fig. 4 is a plan view of discharging wheel upon the crowning machine. Fig. 5 is a plan view of the bottle feeding wheel. Fig. 6 is a section on the line 7—7 of Fig. 5.

In detail there is shown in the drawings a bottle crowning machine of well known construction driven by a belt 10 and having a hopper 12 from which the caps or crowns are fed through a guide 13 to the crowning heads 14 as they are moved to the proper

position. The bottles to be crowned are placed upon the upper end of the plungers or bottle supports 15, each of which lies immediately below one of the crowning heads 14 and vertically reciprocates in a rotary table 42 secured on a vertical shaft 43 which extends through a fixed table 17 mounted on a tubular stand 44 and with the lower end of said shaft 43 resting in a bearing 45 in the lower part of said tubular stand. A beveled gear 46 on the shaft 43 meshes with a beveled gear 47 on a shaft 48 extending laterally out and beyond the stand 44 and on its outer end carries a pulley 117 which is driven by the belt 10 from any suitable source of power. The shaft 43 rotates the table 42 and thereby causes the revolution of the series of bottle supports 15 which at their lower ends travel upon an annular cam track 50 secured within the hollow stand 44 and thus said bottle supports are at the suitable time elevated to carry the bottles up into the crowning heads 14, in the well known manner. The portion of the device so far described is old.

For the purpose of feeding the bottle to the crowning machine, a star wheel 16 is mounted on a vertical shaft 18 and slightly above the crowning machine table 17 and upon the upper end of said shaft, a star wheel 19 is secured which meshes with the crowning heads 14. The star wheel 16 is thus caused to revolve in time with the plungers 15 and the crowning heads 14. Upon the lower end of the shaft 18 and below the table 17 a bevel gear 20 is secured with which a bevel gear 21 upon the horizontal shaft 22 meshes, see dotted lines in Figs. 2 and 3, and upon the outer end of said shaft, projecting through the front face 23 of the table 17, a sprocket wheel 24 is secured. A shaft 25 lies parallel with the shaft 22 and upon its outer end carries a sprocket wheel 26 which is driven from the sprocket 24 by a chain 27. Upon the inner end of the shaft 25, the driving pulley, not shown, of the conveyer belt 28 is secured for delivering the bottles to the star wheel 16. The loose pulley of the belt conveyer 28 is mounted as desired, but preferably on the discharge table 29 of the bottle filling machine. The conveyer's travel is slightly faster than the delivery rate of the bottle filling machine to prevent an over-crowding on the discharge table. The conveyer 28 discharges at the

level of the table 17 and in proximity to the star wheel 16.

The star wheel 16 is shown in detail in Figs. 5 and 6. Said wheel has a top plate 30 with peripheral notches 31 therein and U-shaped plates 32 of the same shape as the notches secured upon the under side of the top plate. A collar 33 is secured centrally of the top plate by means of which the star wheel is mounted upon the shaft 18. A curved guide plate 34 is removably secured to the crowning machine table 17 by means of bolts 35 extending through slotted extensions 36 from said plate. Said plate is secured substantially concentric with the star wheel 16 and extends thereabout substantially 90 degrees and the lower left hand end, see Figs. 2 and 3, extending over the path of the plungers 15 is cut away sufficiently to clear the crescent shaped stops 37 on said plungers 15. A curved guide plate 38 is pivotally secured to the right hand end of the guide plate 34 and the free end thereof is normally caused to bear against the conveyer guide 39 by a spring 40 secured to the guide 34 and bearing against the guide 38.

The operation of my invention is as follows: The crowning machine being driven in the usual manner the star wheel 16 and belt conveyer 28 will also be driven and the filled bottles delivered by hand or otherwise to the conveyer will be carried toward the star wheel 16 and will be caught between the projections thereon and will be carried to the left in the direction of the arrow, see Fig. 2, and delivered to the bottleholders of plungers 15 of the crowning machine after which they will be crowned in the usual manner. Should a bottle from the conveyer meet one of the projections on the star wheel instead of moving into a notch it will be carried to the left, but the guide 38 will yield and the bottle will not be broken but will be yieldingly held until the next notch on the star wheel comes opposite to the bottle when it will be forced into said notch by the spring 40 bearing on the guide 38. The action of the spring 40 and place is always to move the bottle in a reverse direction to the movement of the star wheel 16 and never in the same direction. Breakage is thus prevented. As the bottle is moved by the star wheel it will be given a twisting motion upon the table 17 and will be delivered to

the center of the plungers 15. This adjustment is very important for should the end of the guide 34 be set too near the star wheel 16, the bottle will be caught and crushed against the plunger stop 37. On the other hand, should the guide 34 be set too far out the bottle will not be properly centered against the plunger stop 37 and when the plunger is raised, the neck of the bottle will hit against the crowning head and will be broken. In practice it has been found necessary not only to adjust the guide 34 for each different size of bottle used, but for bottles of the same volume made by different manufacturers as well.

As the bottles are moved onto the bottle holders the necks pass into the notches of a guide wheel 142 which is secured to the main column 41 of the machine and revoluble therewith and as the bottles are discharged from the bottle holders, the guide wheel will steady the necks and keep them from falling. To accomplish this result the discharging faces of the guide wheel arms are curved away from the direction of rotation so that the bottles will be discharged with a gradually decreasing movement and with no sudden jar or fling. The bottles are discharged by the centrifugal movement of the rotary table 42 and wheel 142.

I claim as my invention:

A bottle crowning machine including a fixed table, a star wheel thereon for conveying bottles along the surface of the table, a guide substantially concentric with said star wheel and beyond the periphery thereof and consisting of a fixed portion adjustably mounted on said table at the point where the bottles leave the star wheel, and a movable portion hinged to the forward end of said fixed portion and extending to the point where the bottles enter said star wheel, a spring on said fixed portion of the guide and bearing against the outer surface of said movable portion, and means for limiting the inward movement of the free end of said movable portion of said guide.

In witness whereof, I have hereunto affixed my signature in the presence of the witnesses herein named.

WILLIAM C. MUENCH.
